DESIGN FOR A PEN AND INK DESK-STAND

William F. Deppermann, Orange, N. J., assignor to S. S. Stafford, Inc., New York, N. Y., a corporation of New York

Application March 20, 1937, Serial No. 68,291

Term of patent 7 years

To all whom it may concern:

Be it known that I, William F. Deppermann, a citizen of the United States, residing at Orange, in the county of Essex and State of New Jersey, have invented a new, original, and ornamental Design for Pen and Ink Desk-Stands, of which the following is a specification, reference being had to the accompanying drawing, forming part thereof.

In said drawing:

desk-stand, showing my new design, the ink bottle or ink well being indicated by dotted lines in this figure but being omitted from Figures 2 and 3 for convenience of illustration.

I claim:—

The ornamental design for a pen and ink desk-stand, as shown and described.

WILLIAM F. DEPPERMAN.
